FIG. 1 is a side elevational view of a cuffless sock showing our new design with the tab in a somewhat raised position; and

FIG. 2 is a perspective view of the cuffless sock, looking at the opposite side from that shown in FIG. 1.

The characteristic features of our design reside in the combination of a blanket stitch and depending looped heel tab wherein the blanket stitches extend around the periphery of the foot opening and overlie the upper end of the depending tab and wherein the knitted wales of the tab and the heel extend in the same general direction, all as best shown in FIG. 2.

We claim:

The ornamental design for a cuffless sock, substantially as shown and described.
